ATTY

UNITED STATES PATENT OFFICE.

HERBERT ERNEST ROSS, OF SYDNEY, NEW SOUTH WALES, AUSTRALIA.

HOOK-LINK FASTENER FOR EYELETED WEARING-APPAREL.

1,353,614.

Specification of Letters Patent. Patented Sept. 21, 1920.

Application filed November 29, 1918. Serial No. 264,549.

To all whom it may concern:

Be it known that I, HERBERT ERNEST Ross, subject of the King of Great Britain and Ireland, residing at Equitable Buildings, 5 George street, Sydney, New South Wales, Australia, have invented new and useful Improvements in Hook-Link Fasteners for Eyeleted Wearing-Apparel, of which the following is a specification.

This invention relates to devices for fastening together eyeleted marginal edges of openings in shoes, leggings, corsets, and other articles of close fitting apparel. It 10 consists of a fastener of the double hook-link type, and comprises a link or connector limb of metal armed at one end with a plurality of laterally disposed claws, and at the other end a corresponding number of down-turned catch claws. Fasteners, according 15 to this invention, are characterized in that the fixing or anchoring means at one end of them consists of a plurality of laterally disposed claws which are insertible in adjacent eyelet holes only when the eyeleted margin 20 of the apparel is folded or crimped to offer the necessary entry clearance. These anchor claws are effectively locked in said eyelet holes when the apparel is in its normal shape, but they permit the link to be 25 moved to insert the catch claws in corresponding eyelet holes on the opposite margin of the article or to withdraw said hook claws out of said last mentioned eyelet holes. The term "eyelet holes" is intended to 30 include holes not fitted with reinforcing eyelets.

The known type of double hook fastener, which consists of a rod or bar bent to form two parallel link members cross connected 35 by an integral yoke at the anchor ends and bent to form catch hooks at the extremities, is adapted to be inserted in and attached to one side of the apparel by entering its end upwardly from neighboring eyelet holes 40 therein and drawing it therethrough so that the yoke will underlie the material between said eyelet holes. In that type of fastener the link or limb members are necessarily parallel, and in pairs. In hook fasteners 45 according to the present invention, the laterally disposed anchor hooks may be formed on a buckle-like link member or on the ends of parallel or crossed link members, because the link members are not drawn 50 through the eyelet holes and the anchor hooks and the catch hooks are insertible

into the eyelet holes from the outer side of the apparel.

In the accompanying explanatory drawings, Figure 1 is a partial perspective view 60 of a shoe showing the closure in the upper thereof fastened according to the present invention, the fasteners being formed to simulate a shoe lace arranged in the conventional way; Fig. 2 is a perspective view 65 showing one of my fasteners held in position for insertion of the anchor claws in neighboring eyelet holes, the apparel being shown "doubled up" to offer the necessary entrance clearance for the anchor hooks; Fig. 70 3 is an underneath plan view showing one of the fasteners attached to one side of eyeleted apparel by means of its anchor hooks; Fig. 4 is a sectional elevation showing one of my fasteners securing adjacent eyeleted 75 edges of a piece of apparel, the dotted line showing the lift-up position of the fastener as it appears in the action of fastening the joint; Fig. 5 is a plan view showing a modified form of the same fastener adapted to 80 engage at either end three oppositely disposed eyelet holes; as shoes are commonly made with five eyelet holes on either side of the vamp opening, it is necessary to provide a means for securing the odd fifth pair of 85 eyelet holes. This is accomplished by making one of the fasteners with an additional pair of arms adapted to take the odd pair of eyelet holes; Fig. 6 is a plan view showing another form of the link members, in 90 which they are constituted of parallel bars with a central crossed bar, which might be expanded or shaped according to any desired pattern to form a buckle-like structure; Fig. 7 is a view corresponding with 95 Fig. 6 showing the method of making the Fig. 6 buckle fastener to engage three eyelet holes instead of two eyelet holes for the reason explained with reference to Fig. 5.

The standard form of the fastener is that 100 shown in Figs. 2 and 3. It comprises an X-shaped member 10 which may be conveniently formed by stamping from sheet metal, having its terminals at one end inturned to form anchor hooks 11, and its terminals at 105 the other end downturned to form catch hooks 12. These hooks 11 and 12 are located a distance apart corresponding neatly with the centering of the eyelet holes 13. The anchor hooks 11 are inserted by doubling 110 up one edge of the apparel 14 as shown in Fig. 2, so that the anchor hooks 11 may be

entered through the adjacent eyeleted holes 13 and then spreading the apparel 14 as shown in Fig. 3. The anchor hooks are then held irremovable as long as the apparel is in the normal position. To remove the fastener the apparel edge must be doubled up as shown in Fig. 2 to offer clearance for the withdrawal of the anchor hooks. Fig. 1 shows two of these fasteners 10 in use on a shoe, the anchor hooks and the catch hooks respectively shown in dotted lines.

Where it is necessary to provide a fastener for embracing together three opposite eyeleted holes, an extra pair of arms 16, 17, is attached to the X-link member 10. One of these arms is fitted with a catch hook 15 corresponding with the other catch hooks, and the other said arm is formed with an outwardly disposed anchor hook 18. If this anchor hook 18 were disposed inwardly so that it would lie in the same direction as the adjacent anchor hook 11, it would be liable to work out of the eyeleted hole in which it is set, but by making the anchor hooks alternately inturned and outturned laterally as shown in Fig. 5 complete security for the anchor end of the fastener is obtained. The anchor end of the fastener 30 in this case is inserted by first passing its supplemental limb 16 through its eyelet hole, and then drawing up the material between the two adjacent eyelet holes as shown in Fig. 2 and inserting in said eyelet holes the other two anchor hooks 11 of the fastener in the manner already described with

reference to Figs. 2 and 3. It is quite immaterial what form or design may be applied to the link member of which the hooks form terminals—it may be formed as a 40 buckle-like device, or in the conventional crossed lace type shown in Figs. 2, 3, and 5, or in an H bar type as shown in Figs. 6 and 7.

When the "eyelet" holes are not reinforced with a metallic eyelet, the claws of the fastener are widened and curved so as to minimize risk of distorting and tearing the leather or other material in which the holes are made. 45

What I claim as my invention and desire to secure by Letters Patent is:—

1. A fastener for eyeleted apparel comprising rigidly connected members, a laterally disposed anchor hook at one end of each member, and a catch hook on the other end of each member. 50

2. A fastener for eyeleted apparel as embodied in claim 1, having adjacent anchor hooks bent in opposite directions. 55

3. A fastener for eyeleted apparel comprising rigidly connected members, a transversely disposed anchor hook on one end of each member, and an inwardly bent catch hook on the other end of each member. 60

In testimony whereof I have signed my name to this specification.

HERBERT ERNEST ROSS.
